UNITED STATES PATENT OFFICE.

JAMES MCFADYEN, OF PATERSON, NEW JERSEY.

FOLDING LUNCH-BOX.

SPECIFICATION forming part of Letters Patent No. 577,198, dated February 16, 1897.

Application filed June 30, 1896. Serial No. 597,651. (No model.)

To all whom it may concern:

Be it known that I, JAMES MCFADYEN, a subject of Victoria, Queen of Great Britain and Ireland, (but having legally declared my 5 intention of becoming a citizen of the United States,) and a resident of the city of Paterson, in the county of Passaic and State of New Jersey, have invented a new and useful Improvement in Folding Lunch and other Boxes, 10 of which the following is a description.

The object of my invention is to produce a lunch-box that may be folded together into a small compass after the contents have been removed, so that it may be conveniently carried 15 in the pocket of a coat or other garment.

Other advantages appertain to this form of construction or device, inasmuch as the parts being separate they may be easily renewed when worn and be more readily and conveniently cleaned after use. I may state that the several parts may be made of different materials from each other, as the covers may be made of stamped metal, leatherite, or compressed paper and the sides and ends of the 25 body or folding portion of leather, compressed paper, leatherite, metal, or rubber combined for the purposes to be described hereinafter. I accomplish these purposes by the device described in the following specification and 30 illustrated in the accompanying drawings, in which—

Figure 1 is a perspective view of a box of my improved construction as it would appear when filled and closed. Fig. 2 is a perspective view of the central or body part, the ends being partly folded. Fig. 3 is a side view, part sectional, showing box when folded and closed for the pocket.

Similar letters have reference to similar 40 parts.

In Fig. 1, *a* represents a top lid or cover having the usual surrounding lips to receive and engage the upper part of the body *b*, as shown in Fig. 3.

c is the bottom lid or cover, similar to the upper lid *a*, but is shorter in length and breadth and which receives the lower end of the body *b*. The body *b* or box is formed slightly tapering vertically, the upper edges being 45 slightly longer and wider than those of the lower, so as to enable the lower lid *c* to fit into the upper lid *a* when the box is closed,

as in Fig. 3. The ends of the body *b' b* are so constructed that they may be folded together, the corners *d*, as well as the center *d'*, 55 being flexible, and may be reinforced for durability by the rubber or leather strips *d*, as shown in Fig. 2. Canvas or other fabric may be used for this purpose also. The ends *b' b* may be formed of separate pieces joined together by the flexible strips *d* or reinforced by the strip, in which case the end would be creased vertically in the center and bend at that point, which would also apply to the corner-joints, the strips being cemented or 60 secured to the body in a suitable manner. A strap-loop *e* is secured at each end of the body *b* on the folding parts *b' b* by the rivets *e'*, through which the securing-strap *g* is drawn when the box is filled, as in Fig. 1. The strap 70 *g* is provided with a handle *h*, riveted to it by rivets *h'*, and a buckle *f*, provided with adjusting-holes in the usual manner, as in Fig. 1.

In use the body *b* is extended and its lower edges inserted into the lid *c* when the articles 75 are packed within the interior space and the top cover *a* fitted upon the upper edges. The strap *g* is then passed through the end loops *e* and the buckle *f* secured in the usual manner. When the contents are removed and it 80 is desired to be made portable, the flexible joints of the body *b* are folded, as shown in Fig. 2, and the flattened body-piece laid into the cavity of the lower lid *c*, into which it fits. The upper lid or cover *a* is then placed over 85 the rim of the lid *c*, and the strap *g* is then passed around sidewise twice and secured by the buckle *f*, as shown in Fig. 3.

Having described the construction and use of my newly-improved lunch-box, what I 90 claim as new, and desire to secure by Letters Patent, is as follows:

1. In a folding lunch-box, an open central loose body having its sides and ends tapering upward made of any flexible, tough and durable material, the ends centrally and vertically creased so as to fold inward, each end being provided with a strap-loop, loose top and bottom covers engaging and partly enclosing said central body and a securing- 95 strap, substantially as specified.

2. In a folding lunch-box, an open central body tapering upward on sides and ends, the corners being flexible, and a vertical crease

centrally located in each end to form a bending joint, said corners and central end bending joints being reinforced by a flexible strip on their inner sides, strap-loops secured to each end, a loose top and bottom cover, the said top cover being larger than the bottom cover in length and width, the bottom lid or cover being of such a size that the central

body when folded may lie within its tray in combination with a strap and securing-buckle substantially as specified.

JAMES McFADYEN.
